GEORGE SILL, OF WILKINS, ASSIGNOR TO HIMSELF AND H. H. NEGLEY, OF ELTSBURG, PENNSYLVANIA.

Letters Patent No. 86,598, dated February 2, 1869.

IMPROVEMENT IN SWINGS.

The Schedule referred to in these Letters Patent and making part of the same.

To all whom it may concern:

Be it known that I, GEORGE SILL, of Wilkins, in the county of Allegheny, and in the State of Pennsylvania, have invented certain new and useful Improvements in Swings; and do hereby declare that the following is a full, clear, and exact description thereof, reference being had to the accompanying drawings, and to the letters of reference marked thereon.

The nature of my invention consists in the construction and general arrangement of a swing, which will be hereinafter fully set forth.

In order to enable others skilled in the art to which my invention appertains, to make and use the same, I will now proceed to describe its construction and operation, referring to the annexed drawings, which form a part of this specification, and in which—

Figure 1 is a front elevation;

Figure 2, a side elevation in section; and

Figure 3, a section of the treadle, showing the manner of adjusting the same.

A A represent the frame;

B B, the swinging bars, near the lower ends of which the seat, C, is placed.

The seat C is constructed of two bent pieces, one, a, forming seat and back, and the other, b, forming sides and arms.

The piece a is, at its front end, secured to a cross-bar, c, connecting the two swinging bars, and the ends of the piece b are mortised through the swinging bars, the centre of said piece passing around and supporting the back of the seat, thus giving to the seat great strength and rigidity.

To the lower ends of the swinging bars B B, the adjustable treadle D is pivoted.

The treadle consists of two arms, d d, slotted at the rear ends, and connected, at the front ends, by means of the foot-board E.

A rod, f, passes through the lower ends of the two swinging bars, and passes also through the slots on the arms d d, which are then secured by means of a notched metal plate, h, pivoted, one to each arm, as shown in fig. 3.

By this means the foot-board E can be placed closer to or farther from the seat, thus allowing the swing to be accommodated as well to grown-up persons as to children.

At the front-ends of the arms d d are pivoted metal bars i i, which have two or more holes, in which rods k k are passed.

These rods connect the treadle D with an arm, m, projecting from a segmental wheel, E, which is pivoted, in some suitable manner, to a cross-bar, n, connecting

the two swinging bars a suitable distance from their upper ends.

On the under side of the top cross-bar of the frame A, is placed a stationary segmental wheel, F, which acts in connection with the wheel E, as will be herein-after set forth:

A chain or belt, O, is secured to the arm m, and passes along the front and upper side of the wheel E, then along the rear side of the wheel F, and is secured to the top of the frame A.

The swing is operated by pressing on the treadle with the foot, which, acting through the rods k k on the wheel E, causes the swing to move backward, and, by releasing the pressure on the treadle, the swing moves forward again; and, by repeatedly pressing and releasing the treadle, the swing is operated with great ease.

Instead of using the chain or belt O to connect the two wheels, E and F, they may be provided with cogs, gearing into each other, and said wheels may be either elliptical or circular segments, whichever may be deemed most advantageous for the easier operation of the swing.

Having thus fully described my invention,

What I claim as new, and desire to secure by Letters Patent, is—

1. The treadle D, constructed as described, of the slotted arms d d and foot-board e, and having on each arm a notched plate or bar, h, pivoted to the same, for the purpose of adjusting the treadle, substantially as herein set forth.

2. The seat C, constructed, as described, of two bent pieces, one of which forms the sides and arms, and is mortised into the swinging bars B B, substantially as and for the purposes herein set forth.

3. The combination of the stationary segmental wheel F and pivoted segmental wheel E, arranged and connected substantially as shown and described.

4. Connecting the treadle D to the wheel E by means of the rods k k and pivoted bars i i, substantially as shown and described.

5. The combination of the swinging bars B B, seat C, adjustable treadle D, wheels E and F, and connecting-rods k k, all constructed as described, and arranged to operate substantially as and for the purposes herein set forth.

In testimony that I claim the foregoing, I have hereunto set my hand and seal, this 19th day of December, 1868.

GEORGE SILL. [L. S.]
